The ornamental design for a multi-sided die ring, as shown and described.

DESCRIPTION

FIG. 1 is a front elevation view of a multi-sided die ring showing our new design;

FIG. 2 is a back elevation thereof;

FIG. 3 is a right-side elevation view thereof;

FIG. 4 is a left-side elevation view thereof;

FIG. 5 is a top plan view thereof;

FIG. 6 is a bottom plan view thereof;

FIG. 7 is a perspective view thereof; and,

FIG. 8 is a cross-sectional view thereof, showing the multi-sided die ring.

The broken lines depicting the interior of the ring are for the purpose of illustrating the unclaimed portions of the article and form no part of the claimed design.
